CLAIM

The ornamental design for a combined bottle sterilizer and dryer, as shown and described.

DESCRIPTION

FIG. 1 is a first perspective view of a combined bottle sterilizer and dryer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the combined bottle sterilizer and dryer thereof.

The broken lines shown in the drawings depict portions of the combined bottle sterilizer and dryer that form no part of the claimed design.

1 Claim, 9 Drawing Sheets
